HELMET

Walter R. Hiatt, Norwalk, and Michael M. King, South Gate, Calif., assignors to Bates Industries, Inc., Long Beach, Calif., a corporation of California

Filed July 29, 1963, Ser. No. 76,020

Term of patent 14 years

(Cl. D3—13)

FIG. 1

FIG. 2

We claim:

The ornamental design for a helmet, substantially as shown.
